Looms.

GEORGE CROMPTON, OF WORCESTER, MASSACHUSETTS.

Letters Patent No. 2,516, dated October 22, 1861.

SPECIFICATION.

TO ALL WHOM IT MAY CONCERN:

Be it known, that I, GEORGE CROMPTON, of Worcester, State of Massachusetts, have invented a certain new and useful improvement in Power Looms, and do hereby declare that the following is a full, clear, and exact description thereof, reference being had to the accompanying drawings making part of the specifications, in which—

Figure 1 is an end elevation of a loom with my improvements applied.

Figure 2 is a back elevation, and figures 3 and 4, enlarged detached views of the improvements. The same letters indicate like parts in all the figures.

My improvements relate—first, to the motion which operates the lifter and depresser; and secondly, to the angle of the shed in harness motion of fancy looms.

The movement generally given to lifters and depressers in the harness motion in fancy looms is derived from a crank. While this answers tolerably well in narrow or common looms, it has been found objectionable in broad looms, for the reason that sufficient dwell or pause could not be obtained for the passage of the shuttle. To remedy this, cams have been applied, of such shapes as to give the required pause of motion to the shed of the warp, and thereby allow a free and unimpeded passage for the shuttle.

By wear and tear these cams soon lose their original shapes, and finally become useless, unless frequently repaired or replaced. To overcome this objection, and also obtain a movement which can be readily adjusted for more or less dwell or pause to the shed, is the object of my invention.

In fancy weaving it is highly desirable to obtain such an arrangement. Coarse, heavy yarns cling in shedding, and need opening earlier for the passage of the shuttle than finer yarns. More or less harness also demand an adjustability.

Crompton's Improvement in Looms.

To this end I have invented an arrangement to suit all kinds of yarn and figures, and which I will describe as follows:

In the accompanying drawings the harness motion represented is the well known Crompton harness motion, so called. *a* represents the lathe; *b b*, the loom sides; *c c*, the crank arms; and *m*, the crank shaft; *l* and *n*, the slide rods; *O*, the elevator; and *p*, the depresser. On the end of the crank shaft is a face plate *d*, having a stud or crank *e*, which, moving in the direction of the arrow, communicates motion to a rocking plate *h* through the connector *g*, the crank pin *e* being represented nearly at the top. One-half a revolution of the crank shaft rocks the plate *h* one-quarter of a revolution. The connector *k* attached to stud *i* is on the rocking plate, and stud *j*, on the bracket *u* on the slide rod *l*, conveys motion to said slide rod, and through links *q* and *r* and lever *s*, to which they are attached; also to slide rod *n*.

The shed is now evened; and at the point where the chain cylinder operates to distribute the jacks for another shed, the crank pin *e*, by the motion of the crank shaft, ascends, returning the slide rods and the lifter and depresser then on to their original respective positions. The connection *g*, being short in its proportion to the crank which gives it motion, makes a reduced motion as it passes over the top centre, while the connector *k* gives also a reduced motion, on account of its oscillation towards the centre or stud *t* on which the plate *h* rocks. Thus, as both connectors *g* and *k* are simultaneously moving with reduced speed, the pause or dwell is given to the shed of the warp, which is operated by the lifter and depresser.

This mode of operation, just described, is like that represented at fig. 4, (being an enlarged detached view.) The crank plate *d* is divided into 20 divisions, as shown by red lines and figures. At whatever point during its revolution the crank *e* may be, the studs *f* and *i* will be in positions as per corresponding figures. In their passage the outside row of figures shows the relative positions of the stud *f* in ascending, and the inner row when descending; that of the stud *i* is reversed, the outside representing its descent, and the inner series of figures its ascent, and as also illustrated by the direction of the arrows. In figure 4, as the crank *e* moves in the direction of the arrow from the point represented to the red figure 7, (thus making seven-twentieths of a revolution of the crank shaft,) the stud *i* starts from and returns to the position represented, while the slide rod represented by the vertical red line *q* makes comparatively no movement, as shown by the red figures 1, 2, 3, 4, 5, 6, 7, under the horizontal red line *b'*.

This is the extreme amount of dwell or pause which can be obtained. When less is required, the studs *i* and *j* are raised in their slots; they are raised to the extreme ends of their respective slots, as in figure 3. The amount of dwell is thus much diminished, the crank being in the same relative position, and, making $\frac{7}{20}$, seven-twentieths of a revolution, carries the slide rod considerably farther than in figure 4, as will be seen by the figures under the horizontal red line.

Crompton's Improvement in Looms.

It will be thus seen that, by adjusting the connector *k* by its studs *i* and *j* in different parts of the slot, more or less dwell or pause may be communicated to the slide rods, and through the jacks, which operate the harness, to the shed of the warp, and thereby obtain a more clear and uninterrupted passage for the flight of the shuttle, and also affording a more durable device than such cams as have been used for the purpose, besides the advantages of an adjustable arrangement.

It is obvious that this movement may be applied to different kinds of lifters and depressers used in fancy looms, with slight modifications, to suit the circumstances of the case. But so long as the driving crank operates the rocking plate, and that in turn operates the lifter and depresser in the peculiar manner and for the purpose shown, the principle of my invention is retained.

The second part of my invention is for obtaining a variable incline to the lifter and depresser. In the old Crompton loom, patented Nov. 25, A. D. 1837, the incline is absolute, for the purpose of bringing all the threads of the warp in line with each other, when the shed is open. A patent was issued to me Nov. 14, 1854, for an adjustable lining to the lifter and depresser, which could be set at any angle desired. In both cases, however, the back harness was raised earlier than the front harness. It is desirable that they all commence their movement at the same moment. To effect this, I pivot the lining on the lifter and depresser, as at *w* and *v*, fig. 1. When the shed is evened, these linings are in the same horizontal line as the hooks of the jacks, which are caught by them; and just before the shed is fully formed, the ends of the linings near the front of the loom strike projections *x* & *y*, elevating and depressing them to any angle desired, as seen in figure 1, as these projections *x* & *y* may be adjusted. There is a flat spring to each lining *z* resting upon a pin *a'*, as shown, which, when it leaves the projection, returns it to a horizontal position upon said pin *a'*; it is then in a position for a new distribution of the jacks for the succeeding shed, and they operate again as above described.

By this arrangement, I produce any desirable incline or angle to the lifter and depresser, and, therefore, to the shed, as described, and commence moving the jacks and all the warp threads, as described.

Having thus described my improvement, what I claim as new, and desire to secure by Letters Patent, is—

The operation of the crank on the rocker plate, and the combination therewith of the connection to the lifter and depresser, as and for the purpose set forth.

Also the arrangement of the lifter and depresser for producing an incline to the shed, as above described.

GEO. CROMPTON.
